UNITED STATES PATENT OFFICE.

DAVID A. JOHNSON, OF HAMMOND, INDIANA.

AUTOMATIC JOINTER.

1,218,562.

Specification of Letters Patent.

Patented Mar. 6, 1917.

Application filed May 11, 1916. Serial No. 96,856.

To all whom it may concern:

Be it known that I, DAVID A. JOHNSON, a citizen of the United States, residing at Hammond, in the county of Lake and State 5 of Indiana, have invented a new and useful Automatic Jointer, of which the following is a specification.

The present invention appertains to wood working machines, and aims to provide a 10 novel and improved machine adapted for use as a jointer or for ripping boards, planks, veneer, and the like.

It is the object of the invention to provide a wood working machine for jointing or 15 ripping boards, planks, veneer, and the like, and provided with improved means for feeding the stock automatically after it is once started, the machine having adjustable feed rollers, and adjustable and yieldable presser 20 rollers for holding the stock upon the feed rollers.

It is also within the scope of the invention to provide a machine having the characteristics noted, which is comparatively simple 25 and inexpensive in construction, and which at the same time, is practical, serviceable and efficient for its intended purposes.

With the foregoing and other objects in view which will appear as the description 30 proceeds, the invention resides in the combination and arrangement of parts and in the details of construction hereinafter described and claimed, it being understood that changes in the precise embodiment of the invention herein disclosed can be made within 35 the scope of what is claimed without departing from the spirit of the invention.

The invention is illustrated in the accompanying drawings, wherein:—

40 Figure 1 is a plan view of the machine, portions being broken away.

Fig. 2 is a side elevation of the machine, portions being broken away.

Fig. 3 is an opposite side elevation.

45 In carrying out the invention, there is provided a suitable frame 1 provided at one end with an outstanding horizontal table 2 which can be braced by one or more braces 2^a attached to the frame 1. A set of 50 feed rollers 3 are carried by the upper portion of the frame in rear of the table 2, and said rollers are disposed transversely and are spaced longitudinally. The shafts 4 of the rollers are journaled in bearings 55 5 at the opposite sides of the frame, and said bearings have downwardly projecting

slotted brackets or strips 6 resting against the sides of the frame 1 and adjustably clamped thereto by means of bolts 5^a, whereby when the bolts 5^a are loosened, the 60 brackets 6 and their bearings 5 can be adjusted vertically to bring the feed rollers into different horizontal planes, according to the thickness of the stock being operated upon.

In order to operate the feed rollers simultaneously in the same direction, gears 7 are keyed to certain ends of the shafts 4 at one side of the frame 1 and mesh with idle gears 8 carried by brackets 9 between the brackets 6, said brackets 9 being slotted and being adjustably clamped to the sides of the frame 1 by means of bolts 10, whereby when the bolts 10 are loosened, the brackets 9 the same as the brackets 6 can be adjusted 75 vertically. The rollers 3 are thus operatively connected, and are operated by means of a transverse counter shaft 11 journaled through the sides of the frame adjacent the rear end thereof and approximately in the plane of the shafts 4, said shaft 11 having a gear 12 secured thereon meshing with the rear gear 7. A relatively large pulley wheel 13 is keyed to one end 80 of the shaft 11 and is connected by an endless belt 14 with a smaller pulley wheel 15 secured upon one end of a drive shaft 16 journaled through the sides of the frame, a pulley wheel 17 being secured upon the opposite end of the shaft 16 to be belted to an 85 engine or other prime mover, either directly or indirectly. Thus, when the shaft 16 is rotated, the shaft 11 is rotated at a slower velocity, in order that the feed rollers 3 will be rotated at the proper speed.

90 Mounted for rotation above one side of the frame 1 is a cutter head 18 mounted upon a stub shaft 19 journaled in a pedestal or bearing 20 attached in any suitable manner to the frame. A small pulley wheel 21 is secured upon the shaft 19 and is connected by an endless belt 22 with a larger pulley wheel 23 mounted upon the shaft 16 adjacent the pulley wheel 17, whereby the cutter head 18 is rotated at a high speed. 100 The cutter head 18 is provided with radial slots 24 within which are secured obliquely arranged cutter blades 25 having their sharp edges projecting at an acute angle from the inner face of the head 18, and 105 having their outer ends curved. An idler roller 26 is carried by the frame below the

cutter head between the respective rollers 23, to support the stock where it passes below the cutter head.

A presser device is mounted above the 5 feed rollers 3 adjacent the cutter head, to press the stock upon the feed rollers, whereby the stock will be properly advanced. Said device is adjustable vertically upon a pair of standards 27 attached to that side 10 of the frame 1 above which the cutter head 18 is mounted, and said device includes a longitudinal bar 28 provided at its ends with sleeves 29 slidable upon the standards 27. In order to indicate the vertical position 15 of the presser device, and to enable it to be set at different position, a pointer 30 is attached to one of the collars 29 and cooperates with graduations 31 upon the respective standard 27. The presser device 20 includes a second longitudinal bar 32 parallel with the bar 28 and disposed above the center of the frame, said bar 32 being connected rigidly with the bar 28 by transverse stays or cross pieces 33, whereby the bars 28 25 and 32 and stays 33 provide a presser head or frame. The bars 28 and 32 are provided with vertical guide sleeves 34 through which vertical stems 35 are slidable, wing nuts 36 being threaded upon said stems and seating upon the sleeves 34 to support said 30 stems at different positions, according to the adjustments of said nuts. The bar 28 is provided with an inwardly offset portion 28' passing around the cutter head, as seen in 35 Fig. 1, and the respective guide sleeves 34 are therefore spaced inwardly with respect to the other guide sleeves of the bar 28. The stems 35 are provided at their lower ends with bearings 37 in which are journaled transverse shafts 38 having presser 40 rollers 39 mounted thereon, said rollers 39 being disposed above and parallel with the feed rollers 3. The rollers 39 are preferably covered with rubber or equivalent material. Coiled wire expansion springs 40 are disposed upon the stems 35 between the bearings 37 and guide sleeves 34 and yieldably depress the presser rollers, although the stems 35 can slide upwardly to permit 45 the presser rollers to yield vertically. The downward movement of the presser rollers is limited by the wing nuts 36, which as above indicated, can be adjusted to adjust the positions of the presser rollers. The 50 presser rollers are shorter than the feed rollers 3, and overlie those portions of the feed rollers nearest the cutter head.

As a means for adjusting the presser device as a unit, a vertical screw 41 has the 55 lower end of its shank attached, as at 42, to the same side of the frame 1 as the standards 27, and an upstanding sleeve 43 is attached upon the bar 28 between its ends and slidable upon the screw 41. Said sleeve 60 65 43 is provided with an upstanding yoke 44

provided at its upper end with a sleeve or bearing 45 alining with the sleeve 43, and a sleeve nut 46 is mounted for rotation within the bearing 45, and is provided with a bevel gear 47 intermeshing with a bevel gear 48 secured to one end of a longitudinal shaft 49 journaled through a bearing 50 with which one side of the yoke 44 is provided. The shaft 49 is provided at its rear end with a hand wheel 51 which can be rotated manually for rotating the nut 46, which in being rotated upon the screw 41 will move the yoke 44 either upwardly or downwardly, and the bar 28 of the presser head or frame in being attached to the yoke 44, will cause the presser head to be moved vertically to the desired position. It is thus possible to raise or lower the presser rollers as a whole to accommodate different stock. 70 75 80

In order to regulate the amount of material that is cut from the stock, a longitudinal gage 54 is mounted upon the table 2 in front of the cutter head, and is mounted for transverse adjustment upon suitable slides 55 and 56. 85 90

Another gage 52 is mounted for transverse adjustment upon a slide 53 carried by the forward portion of the frame adjacent the table 2, and is adjustable to various widths of stock. 95

In operation, the board or other stock to be cut, is placed upon the table 2, the gage 54 being properly adjusted to regulate the amount of stock that will be cut away by the cutter head, and the gage 52 is then 100 adjusted to accommodate the width of the stock, so that the stock will be properly guided to and past the cutter head. The stock is then started rearwardly by hand, and as soon as it passes over the first feed 105 roller 3, the stock will be fed automatically by the feed rollers, being pressed downwardly thereon by the presser rollers 39. That edge portion of the stock adjacent the cutter head will be cut away, thereby finishing said edge, the stock being fed longitudinally by the machine without manual attention after the stock is once started. 110 115

Instead of using the cutter head 18, an ordinary circular rip saw can be used, whereby to rip the stock, and cut a strip therefrom, governed by the position of the gage 54, as will be apparent. 120

From the foregoing, taken in connection with the drawings, the advantages and attributes of the invention will suggest themselves to those versed in the art, without further comment being necessary. 125

Having thus described the invention, what is claimed as new is:

A wood working machine comprising a frame, guiding means carried by the frame, a cutter carried by the frame, an upstanding screw secured rigidly to the frame, a presser frame having a sleeve between its 130

ends slideable upon the screw, means for guiding the presser frame for vertical movement, spring depressed rollers carried by the presser frame above said guiding means, an 5 upstanding yoke carried by said sleeve and having a vertical bearing above the sleeve and a second bearing, a nut rotatable within the first mentioned bearing and threaded upon said screw, said nut having a bevel 10 gear at its lower end seating upwardly against the first mentioned bearing, a shaft

journaled through the second mentioned bearing, and a bevel gear secured upon said shaft within the yoke and meshing with the aforesaid bevel gear.

15

In testimony that I claim the foregoing as my own, I have hereto affixed my signature in the presence of two witnesses.

DAVID A. JOHNSON.
